CLAIM

The ornamental design for a cocktail dish, as shown and described.

DESCRIPTION

FIG. 1 is a top view of a cocktail dish showing my new design;

FIG. 2 is a right side elevational view thereof, the left side elevational view being a mirror image thereof;

FIG. 3 is a rear elevational view thereof;

FIG. 4 is a front elevational view thereof;

FIG. 5 is a bottom plan view thereof;

FIG. 6 is an upper axonometric view thereof;

FIG. 7 is a bottom plan view of a second embodiment of a cocktail dish showing my new design;

FIG. 8 is a right side elevational view thereof, the left side elevational view being a mirror image thereof;

FIG. 9 is a rear elevational view thereof, the front elevational view being as shown in FIG. 4; and,

FIG. 10 is an upper axonometric view thereof.
